PAUL MAUSER, OF OBERNDORF-ON-THE-NECKAR, GERMANY; FRIEDRICH EICHHORN, OF OBERNDORF-ON-THE-NECKAR, GERMANY, ADMINISTRATOR OF SAID MAUSER, DECEASED.

AUTOMATIC FIREARM.

1,159,059.

Specification of Letters Patent.

Patented Nov. 2, 1915.

Application filed February 12, 1914. Serial No. 818,235.

To all whom it may concern:

Be it known that I, PAUL MAUSER, subject of the King of Wurttemberg, residing at Oberndorf-on-the-Neckar, Wurttemberg, 5 Germany, have invented new and useful Improvements in Automatic Firearms, of which the following is a specification.

The invention relates to a breech mechanism for automatic firearms, comprising a 10 rotary breech member provided with locking lugs, and consists mainly in the combination of the rotary breech member with a locking member which, in the closed position, engages one of the locking lugs, there- 15 by locking the breech member against rotation, and which, on firing, is automatically released or moved from its locking position, whereby the breech member is free to rotate and to open the breech.

20 The accompanying drawing shows by way of example an embodiment of the invention, in which:

Figure 1 is a vertical longitudinal section through the parts when the breech is closed 25 and locked, the shoulder of the locking member engaging the lug of the breech member being shown in dotted lines. Fig. 2 is a vertical cross section taken on line A—A of Fig. 1. Fig. 3 is a horizontal section through 30 the parts in the same position as shown in Fig. 1. Fig. 4 is a vertical longitudinal section through the front portion of the breech casing. Fig. 5 is a detail view of the end portion of the locking member, in front and 35 side elevation. Fig. 6 shows the coöperation of the locking member with the firing mechanism in side elevation.

Referring to the drawing, the breech mainly consists of the longitudinally dis- 40 placeable breech bolt *k*, the breech closing spring *f*, and the bolt head *v* located rotatably in the said breech bolt and carrying the locking lugs *w*. The breech casing *h*, receiving the barrel *b*, is provided with 45 notches or recesses in the usual manner, the shoulders *i* of which are engaged by the lugs *w* thereby closing the breech.

As shown in the drawing, the lugs *w* and the corresponding shoulders *i* are relatively 50 beveled in such a manner that during firing the said lugs can be withdrawn from the recesses formed in the breech casing, partly owing to the recoil action and partly owing to the remaining gas pressure, and during 55 closure the screwing in of the lugs behind

the shoulders of the notches can take place owing to the pressure exerted by the breech closing spring *f*.

In order to positively lock the breech bolt in the closed position, a separate locking member is provided in conjunction with the said breech mechanism *k*, *v*, *w*, as the locking lugs are of too steep a pitch to effect positive locking by themselves; the effect of the said locking member being to hold the breech block against rotation, *i. e.* to retain the bolt head *v* and its lugs *w* against backward rotation in the closed position until the shot is fired and the gas pressure in the barrel *b* is reduced to the degree admissible for a safe 70 opening.

In the constructional form illustrated, the locking member is a slide *s* displaceable in the direction of the movement of the breech bolt *k* within the wall of the breech casing *h*, so that as soon as the locking lugs have attained the closing position, it also reaches the closed position in a suitable manner and preferably under the action of a spring *g*. It is obvious that the movement may also 80 be effected positively from a moving member of the breech.

The locking takes place by the direct co-operation of the locking slide with the locking lugs, and, to this end, this slide is provided, at its front end, with an inner shoulder *t*, which, in the locked position, is disposed behind or beneath one of the locking lugs *w* (the upper) and thus prevents the bolt head *v* from rotating. In this locking 85 position the slide *s* is located in its rear position as shown in Fig. 3. When the shot is fired, the slide *s* by its inertia moves forward, against the action of its spring *g*, relative to the breech bolt *k* so that the 90 previously retained locking lug *w* can effect its releasing rotation past the shoulder *t* of the slide *s*. It is merely a matter of construction to select the ratios of these parts in such a manner that this releasing rotation and the release of the breech bolt only takes 95 place when the requisite minimum gas pressure is attained. When closing, the converse operation takes place. When the rotation of the bolt head begins, the slide *s* with its shoulder *t* bears, at the front, on the lug *w*. The latter screws past the shoulder *t* inwardly into the recess formed in the sleeve *h*, until finally the lower edge of the lug is located over the upper edge of the 100

110

- shoulder t ; at this moment the rearward path for the spring controlled slide s is free; it can fly backward underneath the locking lug whereby the shoulder t is located beneath and at the rear of the lug: In order to facilitate the operation of the lug and the shoulder, their coöperating edges are formed, as shown in Figs. 1 and 5, with a slightly beveled edge w' and t' respectively.
- 10 For the purpose of insuring safety, provision is preferably made so that the slide s will lock the trigger mechanism, as long as the bolt head is not locked. This can be accomplished as shown in Figs. 3 and 6 by means of a lever l provided with a pin l' engaging a curved guide s^1 of the slide s and coöperating in any known manner with the trigger mechanism (not shown). In this manner firing is impossible until the lug w has completely reached the closed position, and only after this is the case, does the locking slide s rock the lever l in that position in which it releases the trigger mechanism.
- What is claimed is:—
- 25 1. A breech mechanism for automatic firearms comprising a rotary breech member provided with locking lugs and a member

for locking said breech member which in the closed position engages one of the locking lugs thereby locking the breech member 30 against rotation, and which locking member on firing is automatically released from its locking position so that the breech member is free to rotate and to open the breech.

2. A breech mechanism for automatic fire- 35 arms comprising a rotary breech member provided with locking lugs and a slide for locking said breech member, a spring for holding said slide in the closed position in which it engages one of the locking lugs 40 thereby locking the breech member against rotation and which locking slide on firing is automatically released from its locking position by its inertia against the action of its spring so that the breech member is free 45 to rotate and to open the breech.

In witness whereof, I have hereunto signed my name in the presence of two subscribing witnesses.

PAUL MAUSER.
